UNITED STATES PATENT OFFICE.

CHARLES E. MARTIN, OF MANSFIELD, OHIO.

ROOF FOR SILOS OR THE LIKE.

1,032,012.

Specification of Letters Patent. Patented July 9, 1912.

Application filed April 10, 1911. Serial No. 619,974.

To all whom it may concern:

Be it known that I, CHARLES E. MARTIN, a citizen of the United States of America, residing at Mansfield, in the county of Rich-
5 land and State of Ohio, have invented cer-
tain new and useful Improvements in Roofs
for Silos or the Like, of which the follow-
ing is a specification.

My invention relates to roofs for silos or
10 the like.

The objects of my invention are to pro-
vide means of constructing a roof of tapered
corrugated sections of sheet metal; to pro-
vide means of locking all but one of the sec-
15 tions together, leaving a space to be covered
by a single section without interlocking; to
provide a ventilator body with an out-
wardly extending inclined flange to fit the
outer surface of the roof or small ends of
20 the tapered sections; to provide a sleeve
having an outwardly inclined flange to con-
form with the inner surface of the roof on
small ends of the tapered sections, and
means whereby the flanged portions of the
25 sleeve and ventilator can be drawn tightly
together with the small ends of the corru-
gated tapered sections interposed therebe-
tween and rigidly held together. I obtain
these and other objects by the mechanism
30 illustrated in the accompanying drawings in
which:—

Figure 1 shows a cross sectional side ele-
vation of the roof, part of the silo, and the
ventilator. Fig. 2 shows an enlarged cross-
35 sectional side elevation of the ventilator and
method of attaching it to the vertex of the
roof. Fig. 3 shows a side elevation of the
silo with my roof applied thereto showing a
single tapered section attached to a ring
40 and movably mounted upon the ventilator
and adapted to bridge the space between the
interlocked sections. Fig. 4 shows enlarged
views of several tapered sections showing
the method of interlocking them. Fig. 5
45 shows an enlarged view of the movable ring
and one tapered section which is pivotally
attached to the ring and adapted to bridge
the space left open by interlocked sections.
Fig. 6 is an enlarged view of part of two
50 tapered sections showing the method of in-
terlocking them.

In the drawings, reference numeral 1 rep-
resents a silo or the like which can be made
of any form desired. Upright supports 2
55 are attached to the inner periphery of the
silo by screws 2' or any other well known

fastening means, and the free ends are bent
to conform to the angle of the roof that it
is desired to make and are attached to the
under surface of the roof by the rivets a. A 60
series of corrugated tapered sections 3 are
provided to form the roof and locked or
united together to form a conical shape as
shown. In order to securely interlock these
tapered sections together, the end 4 of one 65
section is bent up at an angle as shown in
Fig. 6, and the adjoining edge of the oppo-
site tapered section is bent to form a closed
loop and bent in the opposite direction to
form an open loop as shown at 5 and 6 70
forming a space 7 into which the end 4
is inserted as shown in Fig. 4 and then
forced up until it is made flush with its
companion sections. It will be observed
that the edge 8 of the looped slat is 75
also turned at an angle which coincides
with the angle of the end 4 of the op-
posite slat. This method of interlocking
the tapered corrugated sections of the roof
together provides an efficient means of unit- 80
ing the sections together and effectually pre-
vents rain or the like from working its way
into the silo without the necessity of solder-
ing the sections together. In order to fur-
ther secure the sections together, a through- 85
going bolt 9 is fitted to apertures 10 formed
in the adjoining sections and the nut 11
threadably engages the bolt 9 and when
tightened serves as additional fastening
means. It will be observed that each slat 90
is provided on one edge with a bent end as
shown at 4 and its opposite edge folded or
looped twice to form the space 7 for the en-
gagement of the end 4. All of the tapered
sections are interlocked in this manner to 95
form the conical shaped roof 12 as shown
except an opening 13, equal the dimensions
of one section, is left.

A ventilator 14 having a flanged portion
15 is provided to fit over and extend down- 100
wardly upon the outer surface of the small
ends of the tapered sections. A sleeve 16
having a flange 17 is inserted within the
inner periphery of the ventilator and forced
downwardly until the tapered flange 17 of 105
the sleeve contacts with the inner surface of
the small ends of the tapered sections leaving
the ends of said sections interposed be-
tween the flange 15 of the ventilator and the
flange 17 of the sleeve. L shaped brackets 110
18 are rigidly fastened to the sleeve by
rivets 19, the heads of which are flush with

the outer periphery thereof to permit adjustment of the sleeve within the inner periphery of the ventilator for clamping purposes. Standards 20 are attached to the inner periphery of the ventilator by rivets 5 21 and the lower ends of the standards 20 are bent L shape to aline with the ends of the brackets 18 and both have alined apertures into which a through-going bolt 22 is inserted which a nut 23 threadably engages and when tightened draws the sleeve 16 in an upward direction in contact with the inner surface of the roof, securely clamping together the interposed small ends 10 of the tapered sections which form the roof. The standards 20 support a hood 24 which is fastened to the standards by rivets 25. In order to complete the roof and cover up the opening 13, I provide a ring 26 having a bifurcated portion 27 and pivotally attach a tapered corrugated section 28 thereto. The pivoted connection permits the tapered section 28 to be raised from the position shown 20 in Fig. 3 and the movable ring permits the 25 tapered section to be moved laterally until it is directly over the opening 13, overlapping the edges 29 and 30 of the interlocked corrugated tapered sections and thereby covering the opening 13. In order to hold the single 30 section 28 securely in place, a bolt 31 is provided which passes through apertures in the bifurcated portion 27 of the ring and when drawn up by the nut 31' securely clamps by friction the ring and its attached section to 35 the ventilator.

It will thus be seen that a very efficient roof is obtained and any part can be replaced without affecting any other part of the roof and it can be assembled or taken 40 apart without difficulty. It will further be observed that the roof can be shipped from the factory in a compact form.

What I claim is:—

1. In a roof for silos and the like, a series 45 of tapered sections longitudinally corrugated, one side of each section being bent over upon itself to form a closed loop and being further bent to form an open loop that underlies the closed loop, said side of said 50 section being extended beyond the outer side of the closed loop and being bent upwardly to engage the adjacent side of the adjacent section, said adjacent side of the adjacent section projecting in the open loop, the 55 looped and the extended portion of the one sheet forming the two walls of the final corrugation of that edge of the sheet and being engaged by the two walls of the final corrugation at the complementary edge of the adjacent 60 sheet and fastening means passing through said side of the adjacent section and the upwardly bent side portion of the first mentioned section.

2. A roof for silos, comprising a series of 65 corrugated and tapered interlocking sheet

metal sections, a sleeve having an outwardly and downwardly extending flange to support the small ends of said sections, a spring clamp carrying a non-interlocking section rotatably mounted on said sleeve so as to 70 permit said non-interlocking section to swing in a lateral direction.

3. A roof for silos, comprising a series of corrugated and tapered interlocking sheet metal sections leaving an opening, a sleeve 75 provided with a flange on its lower portion adapted to support the small ends of said sections, a second sleeve having an outwardly and downwardly extending flange formed on its lower portion and adapted to fit and extend over the small ends of said sections, means to movably connect the sleeves together the second sleeve having an annular groove formed thereon, a spring clamp carrying a non-interlocking section 80 rotatably mounted in said annular groove so as to permit said non-interlocking section to swing over the opening left between said sections and away from said opening as described and set forth.

4. In a self-supporting roof, the combination of a series of interlocking corrugated and tapered sheet metal sections arranged to form a cone shaped roof leaving an opening in the center, a sleeve provided with a flange 95 on its lower portion adapted to support the small ends of the sections, means to fasten said small ends to said sleeve, inwardly projecting brackets secured on the inner periphery of said sleeve, a second sleeve provided 100 with a flange and fitted to extend over the outer periphery of said sections, and means engaging said bracket to draw said sleeves together whereby the interposed small ends of the sections are clamped together, substantially as described and set forth.

5. A roof for silos, comprising a series of interlocking and corrugated tapered sheet metal sections, and one movable section, a sleeve adapted to support the small ends of 110 said sections provided with an annular flange to fit the inner surface of the small ends of the tapered sections, a second sleeve having an outwardly and downwardly extending flange fitted to the outer periphery of said 115 sleeve and adapted to extend over the small ends of said tapered sections leaving the small ends of said sections interposed between the outwardly extending flange of the sleeve and the outwardly extending flange 120 of the second sleeve, and means to connect both sleeves together and bind said small ends of the sections therebetween to form a self-supporting roof.

6. A roof for silos, comprising a series of 125 interlocking and corrugated tapered sheet metal sections, a sleeve adapted to support the small ends of said sections provided with an annular flange to fit the inner surface of the small ends of the tapered sections, a sec- 130

ond sleeve having an outwardly and down-
wardly extending flange fitted to the outer
periphery of said second sleeve and adapted
to extend over the small ends of said tapered
5 sections leaving the small ends of said sec-
tions interposed between the outwardly ex-
tending flange of the first sleeve and the out-
wardly extending flange of the second sleeve,
means to connect both sleeves together and
10 bind said small ends of the sections there-
between to form a self-supporting roof, and
a cap carried by the second sleeve.

7. A roof for silos or the like, comprising
a series of interlocking corrugated and ta-
15 pered sheet metal sections, said interlocking
members contacting with and reinforcing

each other to and tending to maintain the
sections in a cone-shaped relation.

8. A roof for silos or the like, comprising
a series of interlocking corrugated and ta- 20
pered sheet metal sections, said interlocking
members reinforcing each other to resist lat-
eral strain, means passing through both in-
terlocking members and to hold the larger
ends of the sections in place and means to 25
securely clamp the small ends of the sections.

In testimony whereof I affix my signature
in presence of two witnesses.

CHARLES E. MARTIN.
